(57) **CLAIM**

The ornamental design for an energy storage device, as shown and described.

DESCRIPTION

FIG. 1 is a perspective view of an energy storage device showing our new design, shown in an environment of use; FIG. 2 is a perspective view thereof;

FIG. 3 is a top view thereof;

FIG. 4 is a bottom view thereof;

FIG. 5 is a front view thereof;

FIG. 6 is a back view thereof;

FIG. 7 is a left view thereof; and,

FIG. 8 is a right view thereof.

The broken lines present in the figures are included for the purpose of showing environmental subject matter and form no part of the claimed design.

1 Claim, 3 Drawing Sheets

FIG. 1

FIG. 2

FIG. 3

FIG. 4

FIG. 5

FIG. 6

FIG. 7

FIG. 8
